UNITED STATES PATENT OFFICE

EMIEL P. SEGHERS, OF CHICAGO, ILLINOIS

TOP FOR PERCOLATORS AND THE LIKE

Application filed April 14, 1923, Serial No. 631,982. Renewed June 2, 1928.

This invention relates to tops for coffee percolators or similar vessels and has for its object the provision of means whereby the glass tops are retained in place without danger of being loosened by heating and cooling, the retaining means being arranged to permit easy removal when desired.

A further object is to provide a percolator top which is economical to manufacture, of improved construction, and convenient and efficient to use.

The invention is exemplified in the combination and arrangement of parts shown in the accompanying drawing and described in the following specification, and it is more particularly pointed out in the appended claims.

In the drawing—

Fig. 1 is a vertical sectional view of a percolator cover showing one embodiment of the present invention applied thereto;

Fig. 2 is an elevation of the glass top removed from the cover;

Fig. 3 is a horizontal section on line 3—3 of Fig. 2;

Fig. 4 is a fragmentary elevation of a slightly modified form of glass top; and

Fig. 5 is a vertical section showing a modified form of seat for the top.

In coffee percolators and perhaps other vessels, it is common to provide a small glass top or inverted bell which is fitted to the cover of the percolator so that the operation may be observed from the outside. The vessel is commonly made of thin sheet material, such as aluminum, and the glass top is fitted into a circular opening in the cover. When the vessel is heated the expansion acts to loosen the glass in its opening since the metal used is commonly non-resilient so that when the surrounding flange is bent outwardly by the expansion of the glass top, it fails to return upon cooling. This loosens the top in the cover so that it is liable to drop out and be broken. Small projections have been provided on the glass top arranged to pass through passageways formed in the rim, the top being partially rotated to bring the projections out of registration with the passage-

ways so that a form of bayonet joint is provided for retaining the glass top in place.

The tops, however, are not uniform in size and shape so that it frequently happens that a particular glass top is too small to be held in its seat by the bayonet joint arrangement and this is especially true after the seat has been expanded by heating and cooling. The present invention provides means for retaining the glass tops in place even though they vary considerably in size and are uneven in shape.

In the drawing, the numeral 10 designates a coffee percolator or other vessel having a cover 11 provided with a glass top 12 which is usually in the form of an inverted bell. The cover 11 is provided with a central opening having a downwardly bent rim or flange 13 extending entirely around the opening. A rim 14 at the lower edge of the bell 12 fits within the flange 13 and a circumferential bead 15 limits the downward movement of the top into its seat. The rim 14 is provided with a pair of projections or lugs 16 and the flange 13 is bent outwardly to form passageways 17, as shown in Fig. 3, through which the lugs 16 are moved when the top 12 is placed in its seat. After the glass top is in place it is rotated to bring the lugs 16 out of registration with the passageways 17 to retain the top in its seat. The lugs 16 are spaced from the bead 15 a sufficient distance to pass entirely through the flange 13 and engage its lower edge.

As explained above, the bayonet joint formed by the lugs 16 and passageways 17 is not entirely adequate to prevent displacement of the top 12 under all conditions. The top may be rotated into position to bring the lugs and passages into registration so that the top will fall from its seat when the cover is opened. Expansion and contraction of the parts may enlarge the seat so that the lug will pass the flange even though it is not in registration with one of the passages 17. To overcome these difficulties I have provided in the rim 14 a series of depressions 18 which are distributed about the outer periphery of the rim. These depressions, as shown at 19 in Fig. 3, have their

inner walls inclined at their ends and the shoulders at their lower edges of the depressions may be provided with inclined notches, as shown at 20 in Figs. 1 and 2. With this form of construction the top 12 is placed in its seat as before described and rotated to bring the lugs 16 out of registration with the grooves 17. A blunt instrument, such as the end of a door key, is then used to force the lower edge of the flange 13 into the depressions 18. This will bring the edge of the flange into engagement with the shoulders at the lower edges of the depressions 18. The depressions are deep enough so that although the glass top may subsequently become slightly loosened by expansion and contraction it will never become sufficiently loosened to permit escape of the glass top from its seat.

When the bayonet joint arrangement alone is relied upon, one of the lugs 16 may readily be moved past the flange 13 since the flange is comparatively soft and the lug has a very limited bearing point. If the flange is bent into the depressions 18, however, each depression has an extended bearing against the lower edge of the flange and the number of depressions distributed about the periphery of the rim cooperate with one another in retaining the top in place. Moreover, the spaced depressions prevent accidental rotation of the glass top when the flange 13 has been pressed into the depressions so that the lugs 16 cannot be accidentally returned to registration with the notches 17.

If it is desired to remove the top for replacement, it is only necessary to forcibly rotate the top through a part of a revolution. When this is done the beveled ends 19 of the depressions will force the inwardly bent portions of the rim back to their original circular formation so that the top may be readily removed when the lugs 16 are brought into registration with the passages 17. If for any reason difficulty is experienced in rotating the top, a pointed instrument may be inserted along the beveled faces 20 to raise the depressed portions of the flange 13 and thus free the flange from the notches 18. This may be desirable if the rim 14 is of very stiff material or if the glass top should become broken so that it is difficult to rotate in its seat. The depressions 20 may be omitted, however, as shown in Fig. 4. If this is done and it is found necessary to pry the depressed portions of the flange from the depressions, an instrument may be inserted between the rim 14 and the flange 13 at the points between the depressions 18 and moved circumferentially to draw the flange from the depressions.

In Figs. 1 and 3, the flange 13 is shown as integral, but it may be found desirable in some cases to slit the flange at spaced points 21 to form tongues 22 arranged to register

with the depressions 18 in order to facilitate forcing the rim into the depressions.

I claim:—

1. In combination, a cover for a vessel having an open seat therein, a closure arranged to fit in said seat and having a peripherally extending recess therein, the portion of said closure forming the lower wall of said recess having its outer surface extending substantially continuously in an arc about said closure, and means on said cover adapted to enter said recess to retain said closure in place. 70 75

2. In combination, a vessel having a top thereon provided with an open seat, a closure for said seat having a rim arranged to extend into the opening thereof and provided with depressions in its outer periphery, and a flange on said cover positioned about said opening and adapted to be forced into said depressions in the periphery of said rim to retain said cover in place in its seat. 80 85

3. In combination, a percolator lid having an opening therein provided with a circumferential flange, and a glass top for said lid provided with a rim positioned in said opening and surrounded by said flange, said rim having spaced depressions in the outer periphery thereof into which portions of said flange may be forced to retain said top in place in said lid. 90 95

4. The combination with a percolator lid having an opening therethrough surrounded by an inwardly bent flange, of a glass top for said lid provided with a rim portion arranged to enter said opening and with a circumferential bead to limit the movement of said top in said opening, said rim portion having projections thereon for engaging the inner edge of said flange to retain said top in place when said top has certain angular positions relative to said lid but to permit removal of said top when in a different angular position, and means for holding said top from rotation in said opening. 100 105

5. In combination, a percolator lid having an opening therein, a glass top for closing said opening, means on said lid and top constituting a bayonet joint to retain said top in position in said opening, and means for holding said top against rotation in both directions in said opening to lock said bayonet joint. 110 115

6. The combination with a percolator lid having an opening therein surrounded by an inwardly bent flange, of a glass top having a portion arranged to fit within said opening, and a projection on said top arranged to cooperate with a passageway in said flange to form a bayonet joint for retaining said top in place in said opening, said top having a depression therein into which a portion of said flange may be forced to retain said top in said lid and prevent accidental rotation thereof. 120 125

7. A percolator cover comprising a sheet metal lid having an opening therein provided 130

- with a circumferential flange, and a glass closure for said opening having a rim portion extending into said opening, said rim portion being provided with circumferentially spaced 5 depressions in the outer face thereof into which the lower edge of said flange may be forced to retain said glass closure in place and prevent accidental rotation thereof.
8. In combination, a sheet metal percolator 10 cover having an opening therein, an inwardly bent flange surrounding said opening, and a glass top for said percolator having a rim portion arranged within said opening and provided with a depression in the face thereof 15 into which a portion of said flange is forced to retain said top in position, the lateral ends of said opening having inclined walls to force the inwardly bent portion of said flange outwardly when said top is forcibly rotated.
9. In combination, a sheet metal cover for 20 percolators or the like having an opening therein surrounded by an inwardly bent flange portion, and a glass closure for said opening having a rim extending therein, said rim having peripherally spaced depressions in the outer face thereof into which portions of said flange are forced to retain said closure in place, the lateral walls of said depressions being inclined to exert a wedging action on 25 the inwardly bent portions of said rim and restore said portions to their outward position when said closure is forcibly rotated and thus free said closure to permit removal thereof.
10. In combination, a cover for a percolator 30 or the like comprising a sheet metal member having an opening therethrough and provided with a flange of sheet metal surrounding said opening, a closure for said opening having a rim extending therein, and a depression in the outer face of said rim into which said flange may be forced to retain 35 said closure in place in said cover, said depression having an inclined wall portion to permit the insertion of an instrument for forcing the inwardly bent flange from said depression.
11. In combination, a sheet metal percolator 40 cover having an opening therein surrounded by an inwardly bent flange, and a glass top having a rim portion extending into said opening and having peripherally spaced depressions in the outer face of said rim, the lateral walls of said depressions being inclined and the lower walls of said depressions 45 having inclined portions to permit the insertion of an instrument into said depressions.
12. In combination, a percolator top having an opening therethrough, a sheet metal 50 flange surrounding said opening, a glass cover having a rim portion extending into said opening, a bead on said cover for limiting the movement of said rim into said opening, and a projection on said rim spaced from 55 said bead a distance substantially equal to the width of said flange and arranged to cooperate with a passageway in said flange to constitute a bayonet joint for retaining said glass cover in position in said opening, said rim having spaced depressions in the outer 60 face thereof for receiving inwardly bent portions of said flange, the lateral walls of said depressions being inclined to force said bent portions outwardly when said closure is rotated, the lower walls of said depressions 65 having inclined portions to permit the insertion of an instrument for forcing the inwardly bent portions of said flange from said depressions.
13. A top for percolators having a substantially cylindrical portion arranged to fit in a percolator cover, said portion having a recess formed therein and extending within the outer cylindrical surface of said portion to receive a holding member on said cover. 70
14. A glass top for percolators comprising a bell-shaped member having a substantially cylindrical rim arranged to enter an opening in a percolator cover, said rim having a peripherally extending recess in the outer face thereof extending within the outer cylindrical surface of said rim, said recess having a portion of the wall thereof inclined outwardly at an oblique angle to said outer cylindrical surface. 75
15. A glass top for percolators comprising a bell-shaped member having a recess formed in the outer face thereof adjacent the edge of said bell for receiving a holding member to retain said top in position on a percolator, 80 said recess having a portion of the wall thereof inclined outwardly at an oblique angle to facilitate disengagement of said holding member on rotation of said top relatively to the holding member. 85
16. A glass top for percolators comprising a bell-shaped member having a series of recesses formed in the outer face thereof adjacent the rim of said bell, said recesses having the lateral walls thereof inclined at an angle 90 to the outer face of said bell. 95
17. In combination, a sheet metal lid for vessels having an opening therethrough, a top for closing said opening and provided with a flange projecting through said opening, and tongues formed on said lid adjacent the periphery of said opening for engaging the flange on said top. 100
18. The combination with a cover for a vessel having an opening therethrough, of a top for closing said opening provided with a flange projecting through said opening, and a flange on said cover surrounding said opening and projecting transversely of the plane thereof, said last-named flange having 105 slits therein to separate said flange into tongues for engaging the flange on said top. 120
19. The combination with a cover for a vessel having an opening therethrough, of a top for closing said opening having a flange pro- 125

jecting through said opening, said cover having a flange thereon surrounding said opening at the edge thereof, the flange on said cover being slitted to separate it into tongues for 5 engaging the flange on said top, the flange on said top having a depression extending within the contour of the outer surface thereof for receiving one of said tongues.

20. The combination with a cover for a vessel having an opening therethrough, of a top 10 for said opening having a flange thereon extending through said opening, said flange having a depression in the outer surface thereof extending within the contour of said surface, and holding means attached to said cover for engaging said depression to retain said top in place in said opening.

21. In combination, a percolator lid having an opening therein, a glass top for closing 20 said opening, means on said lid and top constituting a bayonet joint to interlock said top with said cover, and co-operating means on said top and lid entirely independent of said bayonet joint for resisting rotation of said 25 top in said opening.

22. In combination, a percolator lid having an opening therein, a glass top for closing 30 said opening, means on said lid and top constituting a bayonet joint to interlock said top with said cover, and means on said top other than the part constituting the bayonet joint for co-operating with the part on the lid constituting the bayonet joint for resisting rotation of said top, said last-mentioned 35 means on said top being constrained to move therewith at all times.

23. In combination, a percolator lid having an opening therein, means associated 40 with said opening to form one part of a bayonet joint, a glass top for closing said opening, means on said top to form another part of a bayonet joint and adapted to co-operate with the bayonet joint part on said lid for interlocking the top with said 45 cover, and means on the top other than the means constituting a part of the bayonet joint for co-operating with the means on the lid constituting the bayonet joint for resisting rotation of said top, said last-mentioned 50 means on said top being constrained to move therewith at all times.

24. In combination, a percolator lid having an opening therein, a glass top for closing 55 said opening, means on said lid and top constituting a bayonet joint for interlocking said top in the opening in said lid with freedom of rotation, and means entirely independent of said bayonet joint for resisting rotation of said top in said opening.

60 25. In combination, a percolator lid having an opening therein, a glass top for closing 65 said opening, means on said lid and top for interlocking the top in said opening, and means entirely independent of said interlocking means for resisting rotation of said top.

26. A percolator cover comprising a member having an opening therein, a second member fitted within said opening, and means on one of said members adapted to be deformed to engage the other of said members to prevent removal of said second member from said opening without deformation of said means, said means also preventing relative rotation between said members.

27. In a percolator cover, the combination 75 of a lid having an opening therein and having a continuous flange surrounding said opening, a top having a depending flange and having a depression therein into which a portion of said first mentioned flange is forced to prevent removal of said top from said lid.

28. In a percolator cover, the combination 80 of a lid having an opening therein surrounded by a depending continuous flange, and a top having a flange adapted to be arranged within said first flange and having a plurality of circumferential depressions therein into which portions of said first mentioned flange are forced to prevent removal of said top from said lid.

90 In testimony whereof I have signed my name to this specification on this 10th day of April, A. D. 1923.
